COMBINED FILTER AND PUMP FOR AQUARIUMS

David D. Lovitz, Short Hills, N.J., assignor to
Sternco Industries, Inc., Harrison, N.J.

Filed Aug. 21, 1970, Ser. No. 24,631

Term of patent 14 years

Int. Cl. D23—01

U.S. Cl. D23—4

FIG. 1

FIG. 2

FIG. 3

FIG. 4

FIG. 5

FIG. 6

FIG. 1 is a perspective view taken from the top and front of a combined filter and pump for aquariums showing my new design.

FIG. 2 is a side view thereof.

FIG. 3 is an opposite side view thereof.

FIG. 4 is a perspective view taken from the bottom and rear thereof.

FIG. 5 is a top plan view thereof.

FIG. 6 is a bottom plan view thereof.

I claim:

The ornamental design for a combined filter and pump for aquariums, as shown.
